UNITED STATES PATENT OFFICE.

JOSEPH BARBE FOURNIER, OF PARIS, FRANCE.

THERMOMETER AND OTHER SIMILAR DEVICE HAVING SATURATED VAPORS.

No. 896,526.

Specification of Letters Patent.

Patented Aug. 18, 1908.

Application filed December 21, 1905. Serial No. 292,719.

To all whom it may concern:

Be it known that I, JOSEPH BARBE FOURNIER, a citizen of the Republic of France, residing at Paris, 62 Quai des Orfèvres, in the 5 Republic of France, engineer, have invented certain new and useful Improvements in Thermometers and other Similar Devices Having Saturated Vapors, of which the following is a specification.

10 This invention relates to improvements in thermometers and other similar devices in which the part sensible to heat incloses a saturated vapor the tension of which has for its purpose to act on a manometer or other 15 member sensible to the pressure, located at any distance from the said part sensible to heat.

This invention is closely associated with other inventions described in my application 20 Serial No. 233,158, filed November 17, 1904, and my application Serial No. 290,806 filed December 7, 1905.

The purpose of the said improvements is to locate on a predetermined length the part of 25 the apparatus which is sensible to heat.

Figure 1 is a side elevation partly broken away, showing one form of manometric tube connected with a flexible tube and receptacle, so as to embody the principle of my invention; Fig. 2 is a detail consisting of a section of a different type of receptacle B for connection with the flexible tube c; Fig. 3 is a section showing in section another type of receptacle to be connected with the manometer 30 by means of a pipe c'; Fig. 4 is a section showing still another form of my device in which provision is made for excessively high temperatures due to metallurgical and similar operations.

40 a designates a manometer tube sensible to the pressure of the volatile liquid having a high vaporizing point liquid b which it contains. The said tube is connected by a flexible pipe c with a member d (Fig. 1) sensible to heat 45 and which consists of a receptacle to the center of which the said flexible pipe c extends and which contains a volatile liquid e as well as the vapor f of the said liquid, a part of the same volatile liquid b, quicksilver, for instance, filling the tube a and the pipe c. The orifice g of the latter is located at such a point that all the planes passing through the same divide the capacity of the receptacle d into two equal parts. The quantity of the volatile liquid b is such that the orifice g is always 50 immersed in the said liquid whatever may be

the position of the receptacle d whether upright inclined, or reversed, and in any condition as to temperature, that is whatever may be the dilatations of the several parts of the apparatus; whereby the volatile liquid e and its vapor f are never enabled to penetrate into the flexible pipe c and are thus invariably confined in a certain and well defined part of the receptacle d. On the other hand, the 60 quantity of the liquids b and e is such that, in the ordinary conditions of use of the apparatus, the receptacle d is never completely filled with liquid, in order that the phenomena of dilatation shall have no influence at all on the 65 pressure of the liquids, such pressure being exclusively due to the elastic force of the vapor f.

To make use of the device thus fitted up, the whole of the receptacle d is placed there 75 where the temperature is to be indicated or made use of at a distance. There is the assurance that whatever may be the position of the said receptacle, the vapor f, will be exclusively in contact with the liquid e and the 80 walls of the receptacle d, both the liquid and the walls partaking of the temperature of the inclosure in which the device is located. Any "cold wall" phenomenon is thus avoided, so that the tension of the vapor corresponds exactly to the temperature of the 85 inclosure and the pressure transmitted to the manometer is independent of any influence prevailing outside the inclosure.

The device shown in Fig. 2 only differs 90 from that hereinbefore described in that the receptacle d' is in the shape of a tubular nest, the ends of the tubes extending into the flat casings d'.

In Fig. 3, the receptacle d' is divided into 95 two parts by a flexible air-tight partition h; one of the said parts into which opens the pipe c' extending to the manometer is entirely filled with the hardly volatile liquid b' and the other, part contains the volatile 100 liquid e' and its vapor f'.

When the receptacle has to be subjected to the high temperatures of the metallurgic and other trades the device shown in Fig. 4 may be used.

105 The receptacle comprises two tubes d' and d'' of porcelain or other refractory material having the suitable relative capacities and communicating with each other through the tube d' the inner diameter of which is small. The upper part d'' of the tube d' is inclined 110 and carries a pipe i the inner diameter of

which is small; the said pipe, which may be of porcelain, nickel, iron, or the like, opens into the upper part of a bulb *j* filled with quicksilver or other liquid *b*² which fills the 5 pipe *c*² and the manometer (not shown).

To charge the receptacle *d*⁴ *d*⁵, there may be introduced into the tube *d*⁴ through the opening *d*⁸ located at the upper part of the said tube, a metal or other material *e*² in such 10 a manner that on the said material or the said metal being reduced to a liquid state, it will entirely fill the tube *d*⁴, the pipe *d*⁶, and a part of the tube *d*⁵ up to a suitable level *l*, as shown in Fig. 4. Any metals answering the 15 purpose stated are mercury, cadmium, zinc, silver and such other metals and their alloys as will boil under atmospheric pressure at a rather low temperature. The material which fills the system up to the level *l* is so chosen that its melting point will be in proper relation 20 to the temperature to be measured. Then there is introduced into the free part of the tube *d*⁵ of the pipe *i*, and of the bulb *j*, through a cock *k*, a gas *n*, such as azote, hydrogen, or even the air, under suitable pressure. 25

The system thus charged is introduced into the medium the temperature of which requires to be regularized, a blast-furnace for 30 instance, in such a manner that the branch *d*⁴ shall dip entirely into the said medium, while the upper part *d*⁷ of the tube *d*⁵ passes through the wall *m* of the blast-furnace, as shown in diagram in Fig. 4. In general, all 35 that need to be done is to so arrange the reservoir *d*⁴ *d*⁵ that the temperature of the branch *d*⁵ shall never exceed the temperature of the branch *d*⁴. By varying the length and the shape of the pipe *d*⁶ the tube *d*⁴ may be 40 located exactly at the place where a knowledge of the temperature is most required, and the tube *d*⁵ may be applied along the inner wall of the blast-furnace. When the latter reaches the melting point for the material *e*², the latter passes into a liquid state; then as temperature of the blast-furnace continues to rise, the said liquid material is reduced into a state of saturated vapor, the 45

tension of which is transmitted through the medium of the column of gas above the level 50 *l*, then of the liquid *b*² of the bulb *j*, and of the flexible pipe *c*² to the manometer or other apparatus sensible to the pressure.

When the temperatures to be regularized do not exceed a certain value, the reservoir 55 just described may be entirely of iron or of nickel.

The hereinbefore described arrangement has the effect of localizing with the greatest certitude the sensible part of the apparatus 60 in such a manner as to eliminate the injurious influence of cold walls in those parts of the instrument which extend between the point where the heat is to be measured or regulated and the manometer or other apparatus 65 at the outside. The small diameter of the tubes *d*⁷ and *i*, the previous compression of the gas *n*, and the relatively great density of the metallic vapors, all contribute to prevent the diffusion of the said vapors, so 70 that these vapors remain localized in the branch *d*⁴ and at the bottom of the branch *d*⁵. In this form the elements *d*⁴, *d*⁶, *d*⁵, *d*⁷, *i* and *b*² represent the receptacle described above. 75

Claim—

The combination of a curved tube or manometer, of a movable receptacle or vessel, of a flexible tube which puts the manometer tube in connection with the said receptacle, 80 the end of the flexible tube opening at about the center of the movable receptacle, and of a liquid filling the manometer, the flexible tube, and at least one half of the movable receptacle, so that the vapors given off by the 85 liquid in the remainder of the receptacle are always prevented by the liquid from entering into the flexible tube whatever may be the position or the temperature of the receptacle.

In testimony, that I claim the foregoing as 90 my invention, I have signed my name in presence of two subscribing witnesses.

JOSEPH BARBÉ FOURNIER.
